FITTING TABLE HEATER

Filed Feb. 5, 1926

2 Sheets-Sheet 2

UNITED STATES PATENT OFFICE.

EDWARD J. OVINGTON, OF AUBURNDALE, MASSACHUSETTS.

FITTING-TABLE HEATER.

Application filed February 5, 1926. Serial No. 86,158.

The development of the zylonite spectacle frame as a substitute for bone and shell has required new methods and new devices for bending and shaping the material to fit it to the wearer's face. Zylonite is a cellulose compound and is softened by heat, but in order to obtain the best results in bending and shaping such an article as a zylonite spectacle frame to fit the human features, the application of the heat to the various parts of the frame must be localized at certain parts of the frame to permit a sharp bending and shaping at these points, and must be widely distributed at other parts of the frame which require a long, slow curving bending or shaping.

Various expedients have been devised for this purpose. The parts of the frame to be softened have been placed in boiling water and then shaped, or they have been placed over a candle flame, a small alcohol flame, or other crude source of heat. Where electricity has been used, it has been the common practice to construct a truncated cone on a small round or square toaster or electric grid so that the rising heated air passing through the small opening at the top of the cone may be utilized for the purpose of softening the zylonite. All these expedients are open to the objection that they do not permit that combination of heat localization and heat distribution demanded by the peculiar character and shape of the article being treated.

To the end, therefore, of avoiding the objections existing in earlier types and methods while at the same time providing a heater which will combine the essentials above pointed out, I have devised my present invention. According to it, the heater is constructed and arranged to permit a decidedly localized application of the heat at certain parts of the frame and a wide distribution of the heat at other parts of the frame, as conditions require.

In carrying out my invention, I construct the heater itself as a unit of double purpose and result. In one area, it is arranged to produce a thin, narrow strip of rising heated air bounded and concentrated on its edges by an ascending column of cool air carried along by the heated air. This narrow strip of heated air supplies the concentrated or localized heat as above. In another area,

the heater is arranged on a totally different principle, namely, there is no appreciable rising column of heated air, the air being stopped from ascending into the heater by a baffle plate which acts on its under face as a baffle and on its upper surface as a radiant heat reflector. In this manner, over this area of the heater, a circular or substantially circular hot area of wide distribution is provided in which larger portions of the frame, as for instance, the rim or perhaps the curve in the bow of the spectacle frame may be evenly heated. At the juncture of these two main areas of the heater, there exists a "hot spot", which results from the peculiar physical relation of the two areas to each other. This "hot spot" is used where a small amount of intense heat might be required to quickly soften heavy parts of the frame, such as the nose-piece or the butt piece where the temple joins the rim. These and various other features of advantage which will appear more particularly hereinafter are secured in the heater described and illustrated in the accompanying specification and drawings, throughout which like reference characters are employed to indicate corresponding parts, and in the drawings:

Figs. 1 and 2 are side and plan views, respectively, of a selected embodiment of my heater which well illustrates the principles involved.

Fig. 3 is a section on the line 3—3 of Fig. 1.

Figs. 4 and 5 are sections on the lines 4—4 and 5—5, respectively, of Fig. 2.

Fig. 6 is a detail view of the combined baffle and reflector unit removed.

Fig. 7 is a fragmentary plan view particularly illustrating the "hot spot" of my heater.

Fig. 8 is a diagrammatic section on approximately the plane 5—5, of Fig. 2, and particularly illustrating the production of the cylindrical area of wide heat distribution.

Fig. 9 is a diagrammatic section on approximately the line 9—9, of Fig. 3, and particularly illustrating the thin rising sheet of convected heated air of localized application, and

Fig. 10 is a diagram in plan particularly illustrating the several types and shapes of heated spaces, including the "hot spot" be-

tween the narrow sheet of convected heated air and the substantially circular column of radiant heat.

My heater comprises a base 1 and a superposed shell 2 suitably connected thereto. The base is footed to permit a circulation of air beneath it and in use preferably rests upon a footed insulator 3 resting on the fitting table 4.

10 In plan view, the heater shell preferably has the "banjo" shape shown in Fig. 2. This type of shell has pronounced advantages in that the rims or round portions of the zylonite frames can be softened over 15 the circular area 5 of the shell, and the other parts of the frame can be softened either lengthwise or crosswise over the rectangular part 6 of the shell, the parts 5 and 6 at their juncture defining a relatively 20 limited area which I shall designate as a "hot spot" 7 and where the heat is concentrated to maximum intensity. The top of the shell is perforated, as best shown in Fig. 2, and the base of the shell is also 25 open, as indicated at 8 and 9 in Fig. 4.

Mounted within the shell and suitably insulated therefrom is a coiled resistance wire W. As here shown, the wire W is carried by an insulator of mica or other 30 appropriate material 10, which extends through the elongated part 6 of the shell as a narrow strip 11 and at the circular part 5 of the shell extends as a square portion 12. In assembling the heating unit, 35 the mica insulator is formed by laying two straight lengths of mica strips side by side, after which the strips at one end are separated and bent to the generally square form 12, shown in Fig. 3.

40 By coiling the resistance wire upon the mica insulator, it is possible to arrange the spacing of the wire in the coils closer or farther apart depending upon whether a greater or less intensity of heat is desired 45 at certain points.

Within the circular part 5 of the shell, the ends of the resistance wire are carried beneath the heads of a pair of binding screws 13 which are set through an insulated block 14 mounted on the circular wall 5 of the shell, and the lead wires 15 from the current source are carried through the base and fastened by said screws in electrical contact with the ends of the resistance wires.

50 Set within the circular shell 5, between the lower edge of the mica insulator 12 and the top edge of the base 1, is a combination reflector and baffle plate 16 which 55 is peripherally notched, as indicated at 17. The purpose of this member 16 is two-fold. As a baffle, it deflects the air rising through the aperture 8 and directs it through the notch 17 so that the air passes through 60 the so-called "hot spot" 7 (Fig. 7) exist-

ing at the juncture of the circular part 5 with the rectangular part 6 of the shell. As a reflector, it reflects the radiant heat thrown off by the resistance wire at the square portion 12 of the heat unit.

70 The double action of the member 16 is illustrated diagrammatically in Fig. 8 wherein the heat waves emanating from the resistance wire are indicated by the series of arrows A and are shown as being reflected at B by the reflector face of the member 16, and the action of the member 16 as a baffle is indicated by the series of arrows C. The radiant heat at this part 75 of the shell, therefore, is increased by the heat thrown down from the resistance wire as well as that thrown upward, presenting a space wherein the radiant heat is concentrated as a substantially circular area D. (Fig. 10.)

80 In the rectangular portion 6 of the shell, the generated heat is in the form of a relatively narrow elongated strip or sheet of rising heated air, indicated at E, in Figs. 9 and 10.

85 In Fig. 9 I have attempted to illustrate this diagrammatically by the several series of arrows. In this figure, the arrows F indicate rising currents of air which will be heated as they pass the resistance unit and will rise through the top of the part 6 of the shell as a definite strip or sheet E, as indicated by the arrows group F¹ in Fig. 9. The outside arrows G in said figure indicate currents of air rising through the base which will not be heated appreciably, but the effect of which will be to localize the concentration of the heated strip or sheet indicated by the arrows F¹, as will the currents of air indicated by the arrows H in Fig. 9, and which represent currents of air coming up over the outer edges of the rectangular part 6 of the shell.

90 From the foregoing description it will be evident that I provide three zones of heat application, viz, the zone D of wide distribution, which is produced by the radiant heat given off by the resistance wire about the squared portion 12 and reflected back by the reflector face of the asbestos baffle member 16, which member however acts to prevent any appreciable rising column of heated air from passing through the part 5 of the casting; the relatively narrow, elongated zone E of concentrated heat application which is produced by the rising column of heated air bounded on its edges by an ascending column of cool air carried along by the heated air; and the zone or "hot spot" 7 of intense heat application lying between the zones D and E.

95 Various modifications in the construction and operation of my device may obviously be resorted to, all without departing from the spirit of my invention if within the limits of the appended claims.

What I therefore claim and desire to secure by Letters Patent is:

1. In a heater of the class described, a frame and a heating element associated therewith and constructed and arranged to supply a restricted zone of convected heat and an adjacent enlarged zone of radiant heat, there being a space intermediate of said zones constituting a limited area of intense heat application. 70
2. In a heater of the class described, a base, a superposed shell presenting an enlarged area and an adjacent restricted area, a combination baffle and reflector within said enlarged area, and a heating element associated with said shell and effective within said enlarged area thereof to produce a zone of wide heat radiation within which the baffle acts to prevent any appreciable column of rising heated air and effective within said restricted area of the shell to produce a zone of localized heat convection bounded and concentrated on its edges by an ascending column of cool air. 80
3. In a heater of the class described, a base, a superposed shell presenting an enlarged area and an adjacent restricted area, a combination baffle and reflector within said enlarged area, and a heating element associated with said shell and effective within said enlarged area thereof to produce a zone of wide heat radiation within which the baffle acts to prevent any appreciable column of rising heated air and effective within said restricted area of the shell to produce a zone of localized heat convection bounded and concentrated on its edges by an ascending column of cool air, there being a space intermediate of said zones constituting a limited area of intense heat application. 95
4. In a heater of the class described, a base, a superposed shell presenting an enlarged generally circular area and an adjacent relatively narrow area, a combination baffle and reflector within said enlarged area, and a heating element associated with said shell and effective within said circular area thereof to produce a zone of wide heat radiation within which the baffle acts to prevent any appreciable column of rising heated air and effective within said narrow area of the shell to produce a zone of localized heat convection bounded and concentrated on its edges by an ascending column of cool air. 100
5. In a heater of the class described, a base, a superposed shell presenting an enlarged generally circular area and an adjacent relatively narrow area, a combination baffle and reflector within said enlarged area, and a heating element associated with said shell and effective within said circular area thereof to produce a zone of wide heat radiation within which the baffle acts to prevent any appreciable column of rising heated air and effective within said narrow area of the shell to produce a zone of localized heat convection bounded and concentrated on its edges by an ascending column of cool air. 115
6. In a heater of the class described, a base and a superposed shell presenting a generally circular area and an adjacent elongated relatively narrow area, a heating element associated with said shell and presenting adjacent said enlarged area a surface of wide heat dispersion and adjacent said relatively narrow area a surface of localized heat dispersion, an insulated mounting for said heating element consisting of a pair of insulating strips disposed side by side longitudinally of said elongated area and separated and bent upon themselves within said circular area to present an enlarged heating surface generally approximating the interior configuration of said enlarged area of the shell. 120
7. In a heater of the class described, a base and a superposed shell presenting a generally circular area and an adjacent elongated relatively narrow area, a heating element associated with said shell and presenting adjacent said enlarged area a surface of wide heat dispersion and adjacent said relatively narrow area a surface of localized heat dispersion, said areas at their juncture defining a limited area of intense heat application, an insulated mounting for said heating element consisting of a pair of insulating strips disposed side by side longitudinally of said elongated area and separated and bent upon themselves within said circular area to present an enlarged heating surface generally approximating the interior configuration of said enlarged area of the shell. 130
8. In a heater of the class described, a base and a superposed shell presenting a generally circular area and an adjacent elongated relatively narrow area, a heating element associated with said shell and presenting adjacent said enlarged area a surface of wide heat dispersion and adjacent said relatively narrow area a surface of localized heat dispersion, said areas at their juncture defining a limited area of intense heat application, an insulated mounting for said heating element consisting of a pair of insulating strips disposed side by side longitudinally of said elongated area and separated and bent upon themselves within said circular area to present an enlarged heating surface generally approximating the interior configuration of said enlarged area of the shell, and a combination baffle and deflector disposed within said enlarged area and having a cut-out disposed towards said area of heat application of concentrated intensity. 125
9. In a heater of the class described, a base

- and a superposed shell presenting an enlarged area and an adjacent restricted area, a heating element associated with said shell, and an insulated mounting for said heating element consisting of a pair of insulating strips disposed side by side longitudinally within said restricted area and separated and bent upon themselves within said enlarged area to present an enlarged heating surface generally approximating the interior configuration of said enlarged area of the shell. 10. In a heater of the class described, a base and a superposed shell presenting an enlarged area and an adjacent restricted area, said area at their juncture defining a limited area of intense heat application, a heating element associated with said shell, and a combination baffle and deflector disposed within said enlarged area and having a cutout disposed towards said area of heat application of concentrated intensity. 11. In a heater of the class described, a base and a superposed shell presenting an enlarged area and an adjacent restricted area, said areas at their juncture defining a limited area of intense heat application, a heating element associated with said shell. 12. In a heater of the class described, a frame having an elongated portion and an adjacent enlarged portion, and a heating element associated with said frame and presenting an elongated portion cooperating with said elongated portion of the frame to supply a restricted zone of convected heat and presenting an adjacent enlarged portion cooperating with said enlarged portion of the frame to supply an adjacent enlarged zone of radiant heat. 13. In a heater of the class described, a frame having a narrow elongated portion and an adjacent substantially circular portion, and a heating element associated with said frame and presenting a narrow elongated portion cooperating with said elongated portion of the frame to supply a restricted zone of convected heat and presenting an adjacent substantially circular portion cooperating with said substantially circular portion of the frame to supply an adjacent substantially circular zone of radiant heat and a combination baffle and reflector member within said generally circular zone. 14. In a heater of the class described, a frame having a narrow elongated portion and an adjacent substantially circular portion, and a heating element associated with said frame and presenting a narrow elongated portion cooperating with said elongated portion of the frame to supply a restricted zone of convected heat and presenting an adjacent substantially circular portion cooperating with said substantially circular portion of the frame to supply an adjacent substantially circular zone of radiant heat. 55 60 65

In testimony whereof I affix my signature.
EDWARD J. OVINGTON.
